UNITED STATES PATENT OFFICE.

ERVIN E. STRAWN, OF DES MOINES, IOWA, ASSIGNOR TO THE OMNIGRAPH COMPANY,
OF DES MOINES, IOWA, A CORPORATION.

BLANKET STRETCHER FOR PRINTING ROLLERS.

1,414,104.

Specification of Letters Patent. Patented Apr. 25, 1922.

Application filed July 11, 1921. Serial No. 433,801.

To all whom it may concern:

Be it known that I, ERVIN E. STRAWN, a citizen of the United States, and a resident of Des Moines, in the county of Polk and 5 State of Iowa, have invented a certain new and useful Blanket Stretcher for Printing Rollers, of which the following is a specification.

The object of my invention is to provide 10 a blanket stretcher of simple, durable and inexpensive construction, designed to be used in connection with a printing roller for snugly stretching and holding a blanket on such roller.

15 More particularly, it is my object to provide such a stretcher of the kind hereinafter explained in greater detail, whereby the blanket will be stretched evenly and held taut during the printing operation.

20 A further object is to provide such a stretcher which can be mounted in an extremely small space within the body of the roller.

With these and other objects in view, my 25 invention consists in the construction, arrangement and combination of the various parts of my device, whereby the objects contemplated are attained, as hereinafter more fully set forth, pointed out in my claims, and 30 illustrated in the accompanying drawings, in which:

Figure 1 shows a perspective view of the printing roller equipped with a blanket stretcher embodying my invention.

35 Figure 2 shows a transverse, vertical, sectional view through the roller and part of the stretching mechanism; and

40 Figure 3 shows a vertical, sectional view through the shaft of one of the stretcher rollers, the stretcher roller being shown in end elevation.

In stretching and tightening and holding 45 a blanket on a printing roller as for instance in offset printing, it is highly desirable that the blanket should be evenly stretched and held snug against the roller at all points thereof. The blankets of the kind under consideration may be ordinary rubber blankets or may be metal or paper sheets.

50 Especially where metal sheets are employed, it is a difficult problem to stretch them evenly and hold them snugly against the roller. For instance, it is frequently found that when a metal blanket is placed 55 on the roller by hand, one end will stand

away from the roller for certain portion of its length and then when the edges of the blanket are gripped and pulled, the blanket will not be evenly stretched, and the portion which stood away from the roller will never 60 be snugly engaged against the roller, or if the blanket is stretched tight enough to bring all parts snugly against the roller, it will be found that certain parts of the blanket have stretched or have been pulled 65 out of their true shape.

It is my purpose to provide a blanket stretcher, whereby any blanket and particularly a metal sheet may be so stretched that the sheet will snugly fit against the roller at 70 all points and yet will not be pulled out of shape.

In the accompanying drawings, I have used the reference numeral 10 to indicate generally a printing roller of an ordinary 75 type, which roller is mounted on a shaft 11. The roller has in its surface a longitudinal slot indicated at 12.

Arranged inwardly in the roller from the slot 12 and on opposite sides of said slot are 80 stretcher rollers 13 and 14 mounted on shafts 15 and 16. The shafts 15 and 16 project from the roller 10 at one end thereof, as shown for instance in Figure 1.

On the outer ends of the shafts 15 and 16 are pinions 17 and 18, which are arranged in mesh with each other. On the shaft 16, for instance, outside the pinion 18 is a worm wheel 19, which meshes with a worm 20 on a shaft 21 mounted in suitable bearings 22 90 and 23 substantially at right angles with relation to the shaft 16.

The shaft 21 has an angular head 24 adapted to be engaged by a socket wrench.

The rollers 13 and 14, which I have called 95 the stretching rollers are provided with flattened sides 25 and 26, as shown in Figure 2.

For convenience in description, the parts will be described as though the printing 100 roller 10 were in position with the slot 12 upwardly.

Before the blanket is placed on the roller, the stretching rollers are brought to position where their flat sides 25 and 26 are adjacent to and parallel with each other and stand just below and radially inwardly from the slot 12. The surfaces of the rollers 13 and 14 for a short distance from the upper edges of the flat sides 25 and 26 are smooth, as at 27 and 28. The surfaces of the rollers 110

13 and 14 for a certain distance just beyond the smooth portions 27 and 28 are knurled as at 29 and 30.

The smooth portions 27 and 28 are slightly closer to the longitudinal axes of the stretching rollers than the knurled portions 29. The difference in radius at the smooth portions and the knurled portions is brought out clearly in somewhat exaggerated showing in Figure 3.

In the practical use of my improved device, the blanket 31 is placed on the roller 10 and the edges of the blanket are forced into the slot 12 until they project adjacent to each other between the rollers 13 and 14.

The shaft 21 is then rotated for imparting rotation to the stretcher rollers in the directions indicated by the arrows in Figure 2.

20 It will be seen that when the rollers 13 and 14 are rotated for a very short distance, the smooth portions 27 and 28 will engage and grip between them the ends of the plate or blanket 31.

25 If the blanket is evenly placed on the roller at both ends and entirely around the roller, the blanket will be stretched evenly until the knurled portions engage and grip the blanket. The rollers 13 and 14 are rotated until the blanket is tightly stretched and smoothly and snugly engages the roller 10.

If, as sometimes occurs, the blanket 31 when placed on the roller 10 by hand does not fit in against the roller 10 snugly at all points, but stands away from the roller 10 at one end for instance more than at the other end, it will be seen that if the blanket were then stretched by pulling the edges 40 evenly around the rollers 13 and 14, the end of the blanket which had been looser than the other end would not be stretched tightly, or the other end of the blanket would be overstretched and pulled out of proper shape.

45 With my device, however, I have found in practical use that by providing the smooth surfaces 27 and 28, which first engage the blanket, the blanket is then pulled taut, and if one end is a little looser than the other end on the roller 10, the edges of the blanket nearer the tighter end thereof will slip somewhat on the smooth surface until the blanket has the same tautness at all points in its length end to end of the roller 10.

55 Thereafter the blanket is engaged by the knurled portions 29 and 30 and drawn tight

and snug to a proper position on the roller 10.

On account of the use of the worm gear and worm wheel, the parts are held tight 60 when the blanket has once been stretched to snug position on the printing roller.

Some changes may be made in the details of structure of my improved stretcher device without departing from the real spirit 65 and purpose of my invention, and it is my intention to cover by my claims, any modified forms of structure or use of mechanical equivalents, which may be reasonably included within their scope.

70 I claim as my invention:

1. A blanket stretcher comprising in combination with a roller having a slot therein a pair of parallel stretching rollers adjacent to said slot in the first roller, having flattened faces adapted to stand adjacent to and substantially parallel with each other at one point in the rotation of the stretching rollers, said stretching rollers having adjacent to their flattened faces, corresponding 75 smooth surface portions and adjacent to said smooth portions knurled surface portions, whereby when the ends of a blanket are between said flattened faces and the stretching rollers are rotated, the blanket ends may be 80 first gripped between said smooth portions for permitting some slippage, and subsequently by the said knurled portions for 85 proper stretching.

2. A blanket stretcher comprising in combination with a roller having a slot therein a pair of parallel stretching rollers adjacent to said slot in the first roller, having flattened faces adapted to stand adjacent to and substantially parallel with each other at one point in the rotation of the stretching rollers, said stretching rollers having adjacent to their flattened faces, corresponding smooth surface portions and adjacent to said smooth portions knurled surface portions, 90 whereby when the ends of a blanket are between said flattened faces and the stretching rollers are rotated, the blanket ends may be 95 first gripped between said smooth portions for permitting some slippage, and subsequently by the said knurled portions for 100 proper stretching, the radius of the stretching rollers at the parts having smooth surfaces being slightly less than their radius at their parts having knurled surfaces.

110 Des Moines, Iowa, May 12, 1921.

ERVIN E. STRAWN.
